UNITED STATES PATENT OFFICE.

JOHN HAPPE, OF BROOKLYN, NEW YORK.

DESIGN FOR QUILTING.

SPECIFICATION forming part of Design No. 16,749, dated June 22, 1886.

Application filed January 24, 1885. Serial No. 153,938. Term of patent 7 years.

To all whom it may concern:

Be it known that I, JOHN HAPPE, of Brooklyn, in the county of Kings and State of New York, have invented a new and original Design for Patterns for Quilting, of which the following is a full, clear, and exact description, reference being had to the accompanying drawing, making part of this specification, which represents a front view of a portion of a fabric quilted according to my design.

The design relates to quilting.

a a represent two or more rows of square or diamond-shaped figures, which rows alternate with each other, the sides of one row of figures coinciding with the adjoining sides of the adjoining row or rows of figures. A number of such rows or groups of square or diamond-shaped figures are arranged parallel to and equidistantly from each other, according to the size of the fabric to be quilted. The rows or groups of figures *a a* are separated by intermediate spaces or panels, *b b*, of zigzag

shape, which are of equal width throughout the fabric.

Having thus described my design, I claim as new and desire to secure by Letters Patent—

The design for quilting, consisting of a series of rows of square or diamond-shaped figures having their adjoining sides coinciding with each other, said rows or groups being arranged parallel to and coincident from each other, whereby alternating spaces or panels of zigzag shape are formed between the rows of square or diamond-shaped figures, the angles or corners of the adjoining sides of two rows of the said diamond-shaped figures being in line, as shown and described.

In testimony that I claim the foregoing as my invention I have signed it this 22d day of January, 1885.

JOHN HAPPE.
